(57) **CLAIM**

The ornamental design for a bottle, as shown and described.

DESCRIPTION

FIG. 1 is perspective view of a first embodiment of a bottle, in accordance with the present invention;

FIG. 2 is a rear view of the bottle;

FIG. 3 is a left side view of the bottle; the right side view of the bottle being the mirror image of FIG. 3;

FIG. 4 is a front view of the bottle;

FIG. 5 is a top planar view of the bottle;

FIG. 6 is a bottom planar view of the bottle;

FIG. 7 is a perspective view of a second embodiment of a bottle in accordance with the present invention;

FIG. 8 is a rear view of the bottle shown in FIG. 7;

FIG. 9 is a left side view of the bottle shown in FIG. 7; the right side view of the bottle being the mirror image of FIG. 9;

FIG. 10 is a front view of the bottle;

FIG. 11 is a top planar view of the bottle shown in FIG. 7; and,

FIG. 12 is a bottom planar view of the bottle shown in FIG. 7.

The broken lines immediately adjacent the shaded areas represent the bounds of the claimed design while all other broken lines are directed to environment and are for illustrative purposes only; the broken lines form no part of the claimed design.
